UNITED STATES PATENT OFFICE.

JOSEPH HICKSON AND OSCAR P. BUSHNELL, OF MOUNT GILEAD, OHIO.

JOINT FOR HOLLOW BUILDING-BLOCKS, TUBES, &c.

SPECIFICATION forming part of Letters Patent No. 639,569, dated December 19, 1899.

Application filed April 26, 1899. Serial No. 714,510. (No model.)

To all whom it may concern:

Be it known that we, JOSEPH HICKSON and OSCAR P. BUSHNELL, citizens of the United States, residing at Mount Gilead, in the county 5 of Morrow and State of Ohio, have invented a certain new and useful Improvement in Joints for Hollow Building-Blocks, Tubes, and the Like, of which the following is a specification.

10 Our invention relates to a new and useful improvement in joints for hollow building-blocks, tubes, and the like, and has for its object to provide a simple and effective article of this description, whereby such blocks 15 may be properly alined and anchored together.

With these ends in view this invention consists in the details of construction and combination of elements hereinafter set forth 20 and then specifically designated by the claims.

In order that those skilled in the art to which this invention appertains may understand how to make and use the same, the construction and operation will now be described 25 in detail, referring to the accompaniments, forming a part of this specification, in which—

Figure 1 is a section of the ordinary building-blocks having our improved joint-support 30 in position therein, illustrating the manner of anchoring the blocks in position; Fig. 2, a plan view of one of the joint-supports placed in position, and Fig. 3 a view of the blank from which the joint-support is made.

35 In carrying out our invention as here embodied, A represents the blank, which is formed from a strip of metal, paper, or other suitable material, so grooved as to strengthen the same and form a recess B, for the purpose hereinafter set forth. This blank is cut

40 as shown at C, or it might be crimped, and is bent at this point to produce an approximately-rectangular support, as clearly shown in Fig. 2, and also has tongues D, formed by the partial cutting out of sections of the blank, and when these tongues are bent outward in the completed support they will bear

45 against the end of the blocks or pipes, and thus hold the support in position while the 50 mortar or jointing-cement is being applied for the setting of the next block, and regu-

late the space between the blocks or tubes, thus making the joints all of one width.

The side E is left somewhat longer than the other sides of the support and may be sprung 55 inward, as shown in Fig. 2, so as to facilitate passing the support within the block, and then by forcing this side outward the support will be crowded tightly therein. This arrangement of the support provides for adjusting the same within certain limits to fit varying-sized openings in the blocks.

In practice each support is set within the block to about half of its width and rests against the spacer or tongue D. When the 60 mortar, as indicated at F, is applied, it will fill into the space B, formed by the grooving of the support, so that when the next block is passed over the protruding portion of the support it will be tied or anchored to the 65 former block by the support and the mortar or joint material crowding into this space.

A wall built of hollow blocks having our joint-supports therein will be much more rigid and better exclude the water and cold than 70 where the blocks depend only upon the mortar upon their meeting edges to hold them in place and make a tight joint.

Another advantage of our improvement is that in the laying of the blocks a protection 75 is provided against the surplus mortar falling into the center of the blocks, as the projecting support prevents this and clenches the joint material.

In laying the last course of blocks a flexible 80 roll should be run through the holes in the joint-supports in order that said supports may be sprung out to their proper places when the blocks are in position.

The cost of manufacture of a support in 85 accordance with our improvement is exceedingly small, as it may be made entirely by automatic machinery, and consists principally in rolling, and thus adds but little cost to the construction of walls made from hollow 90 blocks, and yet greatly increases their rigidity and makes a marked saving in time and labor.

Having thus fully described our invention, what we claim as new and useful is—

1. As a new article of manufacture, a joint-support for hollow building-blocks consisting

of a strip of material so rolled as to produce a central groove, sections in which a portion of the stock is cut, whereby the blank may be readily bent into shape, as specified.

5. 2. In combination with hollow building-blocks, tubes, &c., a joint-support approximately rectangular or circular, having a central groove in which a bead of mortar is formed when joining the blocks or tubes, as shown 10 and described.

3. A joint-support for hollow building-blocks consisting of a strip of sheet metal so rolled and bent as to produce approximately a right angle having a central groove therein, 15 and tongues bent outward, as and for the purpose set forth.

4. A joint-support for hollow building-blocks consisting of a strip of sheet metal of approximately-rectangular shape, the ends 20 of said support being left free, one end being

longer than the other whereby the support may be crowded within the block and made adjustable for varying sizes, as specified.

5. A joint-support for building-blocks, pipes and the like consisting of a strip of 25 suitable material of suitable shape, the ends of said support being left free, and a tongue partially cut from the material and bent outward to bear against the ends of the blocks or pipes, said strip being cut at suitable 30 points so as to provide for its bending, as specified.

In testimony whereof we have hereunto affixed our signatures in the presence of two subscribing witnesses.

JOSEPH HICKSON.
OSCAR P. BUSHNELL.
